UNITED STATES PATENT OFFICE.

THOMAS E. HEETER, OF ST. LOUIS, MISSOURI.

MACHINE FOR MAKING BOOK COVERS.

Application filed January 17, 1921, Serial No. 437,941. Renewed April 23, 1923.

To all whom it may concern:

Be it known that I, THOMAS E. HEETER, a citizen of the United States, residing at the city of St. Louis, Missouri, have invented a new and useful Machine for Making Book Covers, of which the following is a specification.

This invention relates to improvements in book making machines, and consists in the novel construction hereinafter disclosed.

Heretofore in practice in making book covers or cases, desk blotters, or other similar articles having round corners and comprising a stiff back or card board or heavy paper covered with leather or cloth, the leather or cloth has been turned over the edges of the book and the rounded corners formed by hand. Under this practice much labor has been employed and, in addition thereto, it has been very difficult to obtain a smooth finish at the corners of the articles.

It is the principal object of the present invention to provide a machine whereby the rounded corners for book covers or cases, desk blotters and the like may be formed mechanically and whereby a smooth even finish of the corners will be produced.

This object as well as additional advantages may be obtained from the following described mechanism taken in connection with the accompanying drawings, in which—

Fig. 1 is a front elevation of the complete machine.

Fig. 2 is a side elevation with a portion broken away to better illustrate the mechanism.

Fig. 3 is a fragmentary view in plan of the work supporting bed of the machine.

Fig. 4 is a view of the end of the plunger.

Fig. 5 is a corner section of the blank before the edges of the cover are turned over.

Fig. 6 illustrates the first operation in forming a corner.

Fig. 7 is the next operation with the edges of the covering turned over the back of the blank.

Fig. 8 is the third operation showing the plunger in section.

Fig. 9 is the completed product of the machine.

In the embodiment of the invention illustrated in the drawing the machine is shown as comprising a base 1 supported by suitable legs 2. The mechanism for turning in and creasing the covering for the board of the

book case at the corners includes a work supporting bed plate 3, which is provided with suitable guide pins 4 for holding the work in proper alinement. A finger blade support is mounted on the bed plate 3 and comprises a frame formed from spaced segmental blocks 5 that converge to a common center, the spaces between the blocks constituting guide ways for the finger blades 6. A segmental retaining plate 7 is fitted over the blocks 5 to hold them in position and to prevent the finger blades from displacement. The finger blades 6 radiate from a common center and extend at one end into a cut-out space 8 at the center of the finger blade support and at the other end beyond the outer edge of the finger blade support and are arranged to slide in the support on converging radial paths of movement.

The frame of the machine includes side members 9. The side members 9 support at the front of the machine a front frame comprising uprights 10 and cross members 11. The main operating shaft 12 of the machine is supported transversely of the machine 80 and journaled in the side members 9, the shaft 12 being provided with an operating pulley 13 whereby the same may be rotated.

Below the base plate 1 of the machine is a short stud shaft 14 on which is slidably mounted a spool 15. For each finger blade 6 there is provided a tri-armed lever 16, each lever being pivoted on a bracket 17, said brackets being secured to the under face of the bed plate and being disposed in an arc 90 in alinement with the respective finger blades 6. Through the bed plate in back of the finger blade support is an arcuate slot 18, through which one arm of the tri-armed levers extends. In each of the finger blades 95 near the outer end thereof is a notch 19, each finger blade engaging over the edge of the respective arm of the tri-armed levers 16, so that as the levers are moved on their pivots the finger blades will slide toward 100 and away from their converging center simultaneously.

Each of the levers 16 has connected therewith a spring 20 attached to its lower arm at one end and to the end of the stud shaft 14 at the other end. The tendency of the springs 20 is to normally hold the finger blades 6 in their outward adjustment.

The third arm of each of the tri-armed levers 16 is provided with an adjusted screw 110

21 that abuts against the flange of the spool 15. Obviously, as the spool 15 is depressed the tri-armed levers 16 will be rocked so as to throw their upper arms inwardly, thereby 5 actuating the finger blades 6 inwardly toward their converging center. The means for operating the spool 15 comprises a pair of rods 22 slidably mounted in the bed plate of the machine and normally bearing against 10 the top flange of the spool 15. These rods are in alignment with plungers 23 slidably mounted in the front member of the frame of the machine. The two plungers 23 are connected together by a block 24. The 15 block 24 has threaded therein an adjusting screw 25 that extends above the upper edge of the block behind the front member of the frame of the machine. The lever 26 is pivoted on a shaft 27 supported near the back 20 edge of the side members 9 of the frame of the machine. The lever 26 bears against the end of the adjusting screw 25 at its forward end and carries approximately midway its length, on its side face, a cam roller 28. The 25 main operating shaft 12 of the machine is provided with a cam 29 that cooperates with the cam roller 28 to depress the plungers 23 and thereby the spool 15 through the connecting rods 22, thus swinging the tri-armed 30 levers 16 on their pivots to move the finger blades inwardly. The extent of movement of the finger blades may be adjusted by means of the screw 25.

In order to crease and press down over 35 the board the turned-in corners of the leather or cloth, a plunger 30 is mounted to reciprocate in suitable supports carried by the frame of the machine. The plunger 30 is provided with a head comprising a circular center portion 31 with a series of ribs 32 arranged around the center portion in spaced relationship so that there will be grooves or channels between the ribs. The 40 grooves or channels converge to a common center which is the axis of the central portion 31, the outer edges of the ribs being beveled in order to guide the finger blades into the channels between the ribs and to form smooth creases in the material at the corners. 45 This plunger is normally actuated to raised position by a spring 33 attached at one end to a pin 34 carried by the plunger and at the other end to a pin 35 on the frame of the machine. In order to depress the plunger 50 against the tendency of the spring 33 there is provided a lever 36 pivoted on a rod 37 mounted in the upper rear portion of the frame of the machine. This lever is connected with another lever 38, likewise pivoted on the rod 37, and connected with the lever 36 through an adjusting screw 39. The screw 39 threads into projections on the levers 36 and 38 and is arranged with a fine thread near the upper portion and a coarse thread near the lower portion so that a

relative adjustment of the levers may be effected.

This adjusting screw provides for determining the length of stroke of the plunger 30 in order to accommodate the machine for 70 operation upon case blanks of different thickness. The lever 38 carries at its free end a cam roller 40 that cooperates with a cam 41 on the main operating shaft 12 of the machine. 75

The cams 29 and 41 are so formed and adjusted as to provide the following sequence of operation. In the initial position of the machine the plunger 30 is elevated and the finger blades are in their outward adjustment. In the initial position the machine receives the case blank which comprises the board 42, to the outer face of which is secured the covering 43 of the leather, cloth or other material, with a margin of the 80 covering projecting beyond the edge of the board. The projecting margin of the covering is treated with glue that is allowed to dry to a tacky state. A corner of the case blank is inserted against the edges 85 of the blocks 5 within the cut-out portion of the finger blade support, with the inner edges of the finger blades adjacent to the curved margin of the blank. From the initial position the plunger 30 is depressed 90 against the work supporting bed of the machine by rotation of the operating shaft 12 and the operating connections as described. 95

After the head of the plunger 30 has been positioned a continued rotation of the main 100 shaft through the operating connections described, moves the fingers simultaneously inwardly a slight distance into the space between the ribs 32. The case blank, before insertion in the machine is illustrated in Fig. 105 5; and the first operation just described, whereby the fingers have moved slightly into the channels between the ribs forming the head of the plunger 30, is illustrated in Fig. 6. This operation raises the marginal section 110 of the cover and uniformly creases it at the corner of the case blank, whereupon the plunger 30 is elevated and the finger blades are caused to continue their inward movement, during the elevation of the 115 plunger 30, thereby turning in and holding in place the marginal edge of the covering, as illustrated in Fig. 7 of the drawings. After the finger blades have completed their 120 inward movement the plunger is again depressed, the lower face of the plunger head coming into pressure contact with the surface of the turned-in marginal edge of the covering, as illustrated in Fig. 8 of the drawings. 125

After this operation has been completed a continuation of the rotation of the main shaft raises the plunger 30 and moves the finger blades outwardly releasing the work. The completed product is illustrated in 130

Fig. 9 of the drawings. After the corners have been secured, the straight marginal edges may be glued in position in the usual manner.

5 I am aware that the invention may be modified in certain particulars without departure from the spirit and scope thereof. I do not limit myself therefore to the exact construction and arrangement shown 10 and described, but what I claim and desire to secure by Letters Patent, is:—

1. In a machine of the character described, a work support, a plunger adapted to reciprocate above said work support, a head carried by said plunger having radial grooves formed therein, a finger blade support arranged on said work support, a plurality of slidable finger blades mounted in said finger blade support, said blades being adapted to 15 move into the slots in said plunger head, springs normally actuating said blades outwardly, mechanism for moving said finger blades inwardly, and mechanism for reciprocating said plunger.

25 2. In a machine of the character described, the combination of devices adapted to form a series of radial creases in the marginal edges of the rounded corners of the cover of a book case blank or the like, turn the 30 marginal edges in backwardly on the board of the blank, and hold the same in position, another device to press down the turned-in edge of the cover after the first named devices have performed their stated operations; and operating mechanism for all of 35 said devices timed to perform said operations in the sequence stated.

3. In a machine of the character described, a work support, a plunger adapted to reciprocate above said work support, a head carried by said plunger having radial grooves formed therein, a finger blade support arranged on said work support, a plurality of slidable finger blades mounted in 40 said finger blade support, said blades being adapted to move into the slots in said plunger head, mechanism for moving said finger blades, and mechanism for reciprocating said plunger.

50 4. In a machine of the character described, a work support, a plunger adapted to reciprocate above said work support, a head carried by said plunger having radial grooves formed therein, a finger blade support arranged on said work support, a plurality of slidable finger blades mounted in 55 said finger blade support, said blades being adapted to move into the slots in said plunger head, mechanism for moving said finger blades, mechanism for reciprocating said plunger, and means for adjusting the length of stroke of said plunger.

60 5. In a machine of the character described, a work support, a plunger adapted to reciprocate above said work support, a

head carried by said plunger having radial grooves formed therein, a finger blade support arranged on said work support, a plurality of slidable finger blades mounted in said finger blade support, said blades being 70 adapted to move into the slots in said plunger head, mechanism for moving said finger blades, mechanism for reciprocating said plunger, and means for adjusting the extent of movement of said finger blades. 75

6. In a machine of the character described, a work support, a plunger adapted to reciprocate above said work support, a head carried by said plunger having radial grooves formed therein, a finger blade support arranged on said work support, a plurality of slidable finger blades mounted in 80 said finger blade support, said blades being adapted to move into the slots in said plunger head, mechanism for moving said finger blades, mechanism for reciprocating said plunger, means for adjusting the length of the stroke of the plunger, and means for adjusting the extent of movement of said finger blades. 85

7. A machine of the character described, comprising a work support; a frame; a plunger mounted in the frame and adapted to reciprocate perpendicularly with respect to said work support; a head carried by the lower end of the plunger having a series of radial slots therein; a plurality of finger blades mounted to slide radially toward the axis of the plunger into the slots in the head thereof; means for normally holding the finger blades away from the plunger head; power mechanism for moving the finger blades in opposition to said means, including a lever and a cam device; and means including adjustable levers and a cam device for reciprocating the plunger toward the work support twice during the inward movement of the finger blades. 95 100

8. A machine of the character described, comprising a work support, a frame, a plunger mounted in the frame and adapted to reciprocate perpendicularly with respect to said work support, a head carried by the lower end of the plunger having a series of radial slots therein, a plurality of finger blades mounted to slide radially toward the axis of the plunger into the slots in the head thereof, means for normally holding the finger blades away from the plunger head, power mechanism for moving the finger blades in opposition to said means, and means for reciprocating the plunger toward the work support twice during the inward movement of the finger blades. 110 115 120

9. A machine of the character described, comprising a work support, a frame, a plunger mounted in the frame and adapted to reciprocate perpendicularly with respect to said work support, a head carried by the lower end of the plunger having a series of 125 130

radial slots therein, means for normally actuating the plunger away from the work support, a plurality of finger blades mounted to slide radially toward the axis of the plunger into the slots in the head thereof, means for normally holding the finger blades away from the plunger head, power mechanism for moving the finger blades in opposition to said means, and means for reciprocating the plunger toward the work support twice during the inward movement of the finger blades.

10. In a machine of the character described, a work support, a plunger adapted

to move perpendicularly toward and away from said work support, a head on the plunger having vertical die-slots therein and a presser blade at its base, a series of radial fingers movable toward and away from the axis of the plunger, and means for operating the fingers and the plunger whereby material will be pressed into the slots in the plunger head, released, turned in, and pressed down to form a smooth turned-in corner of a covering over a rounded corner of the board of a book case blank, or the like.

THOMAS E. HEETER.
